United States Patent Office

Des. 213,157
Patented Jan. 7, 1969

213,157

TAPE CASSETTE CONTAINER

Robert S. Wallace, 2706 S. Robertson Blvd.,
Los Angeles, Calif. 90034

Filed Nov. 22, 1967, Ser. No. 9,513

Term of patent 3½ years

U.S. Cl. D87—1
Int. Cl. D3—99

FIG-1

FIG - 4

FIG. 1 is a front perspective view of a tape cassette container showing my new design in partly open condition;

FIG. 2 is a rear perspective view thereof showing the top and side opposite that shown in FIG. 1;

FIG. 3 is a side elevation thereof in closed condition; and

FIG. 4 is a rear bottom perspective view thereof in closed condition.

I claim:

The ornamental design for a tape cassette container, substantially as shown.
